UNITED STATES PATENT OFFICE.

VALÈRE ALFRED FYNNE, OF LONDON, ENGLAND.

ALTERNATING-CURRENT MOTOR.

902,336.

Specification of Letters Patent. Patented June 21, 1910.

Application filed July 9, 1909. Serial No. 506,729.

To all whom it may concern:

Be it known that I, VALÈRE ALFRED FYNNE, a subject of the King of England, residing at London, England, have invented a certain new and useful Alternating-Current Motor, of which the following is such a full, clear, and exact description as will enable any one skilled in the art to which it appertains to make and use the same, reference being had to the accompanying drawings, forming part of this specification.

My invention relates to means for starting and operating single phase induction motors in which the induced winding responsible for the operation of the motor is permanently closed on itself independently of any commutator. It is known that motors of this type have distinct mechanical advantages and good operating characteristics but are difficult to start with a powerful torque and with a small current, or in other words, with a large torque per ampere.

One object of my invention is to provide such means for starting said motors with a large torque per ampere as will not make it necessary to dimension or dispose the secondary working winding permanently closed on itself with any other objects in view but those of highest effectiveness and efficiency under normal running conditions.

Other objects of my invention are to avoid the use of all automatic short-circuiting devices inside the rotor, to provide means for compensating such machines and to generally improve their characteristic properties both at starting and under normal working conditions.

I achieve my object by providing my motor with a rotor having a permanently short-circuited winding extending over all the rotor laminations and with a commuted winding extending over a part only of the rotor laminations; by conveying a working current to the commuted winding and neutralizing the effects of this current on the short-circuited winding; by producing a motor flux threading the commuted winding and adapted to produce a starting torque with the ampere turns due to the working current while neutralizing the effects of said motor flux on the short-circuited winding; by inducing currents in the short-circuited winding either at the moment of starting or after the motor has reached a sufficient speed, thus limiting the speed of the machine and converting same into a self-ex-

cited shunt induction motor and finally by impressing on the commuted winding, preferably after the motor has reached a sufficient speed, an E. M. F. of suitable phase for improving the power factor, *i. e.* for compensating the motor. I may make the necessary changes in the connections automatically or by hand. If an automatic, for instance a centrifugal, device is used it can be placed outside the motor; it can, therefore, always be made easily accessible, can be kept in good condition and can be quickly repaired or replaced.

In describing some ways of carrying my invention into practice I will refer to the accompanying diagrammatic drawings where—

Figure 1 shows a motor provided with two main windings, arranged to start as a neutralized series conduction motor and capable of being compensated. Fig. 2 shows a motor provided with one main winding, arranged to start as a neutralized series conduction motor with the field winding disposed on the rotor. Fig. 3 shows a motor provided with one main winding, arranged to start as a neutralized series conduction motor, the E. M. F. impressed on the starting circuit being derived from the main winding and capable of being compensated. Fig. 4 indicates the mechanical disposition of the motor parts for the machine shown in Fig. 3. Fig. 5 shows a motor provided with two main windings, arranged to start as a shunt conduction machine and capable of being compensated. Fig. 6 shows a motor provided with two main windings and arranged to start as a self-excited series induction motor.

In Fig. 1 the stator carries two longitudinally displaced main or primary windings 7, 8 disposed along parallel axes. Coaxially with 7 is disposed an auxiliary winding 54 and another auxiliary winding 99 is displaced by $180/n$ degrees with respect to 7 and 54. The letter *n* stands throughout for the number of poles of the motor. The rotor carries a permanently short-circuited working winding 24, 25 embracing all the rotor laminations and a commuted winding 34 embracing part only of the rotor laminations. The secondary short-circuited working winding is shown, mainly for convenience and clearness of illustration as consisting of two longitudinally displaced and permanently interconnected windings 24, 25.

They are shown as being interconnected at four points, but they can be interconnected at any desired number of points, the more the better. In practice a single winding of 5 some simple form would preferably be used. The figures disclose the starting position of the various switches. From main 1 the current flows through 7 to point 51 also through the reversing switch 53 and through 10 8 to point 51, thence to switch 71, the neutralizing winding 99 to brush 36 through the commuted winding 34 to brush 37 and to main 2. It is seen that 7 and 8 magnetize in opposite directions, accordingly the windings 24, 25 representing the short-circuited working winding are so connected that no current will flow in that winding as long as 15 7 and 8 are connected as shown. This is diagrammatically illustrated by connecting points 28, 29; 26, 27; 32, 33 and 30, 31. The main fluxes due to 7 and 8 are as nearly equal as possible and will therefore thread the short-circuited winding 24, 25 without inducing any current in it provided an equal 20 25 or equivalent number of turns of said winding is threaded by each main flux. The current is conducted in opposite directions through 99 and 34, the neutralizing winding 99 being so arranged and dimensioned that 30 no flux threads the rotor and stator along the axis of the brushes 36, 37. The effect of the working current in winding 34 on the short-circuited winding 24, 25 is therefore neutralized. The main flux due to 7 is practically in phase with this working current and does duty as motor field at starting. When the motor has reached a sufficient speed the current through 8 is reversed at 35 53 thereby bringing the short-circuited rotor 40 working winding 24, 25 into play. This winding will now act as the secondary of an ordinary induction motor. Switch 71 is now moved on to point 106 thereby cutting 45 99 out of circuit and if compensation be desired then switch 21 is closed thereby impressing a compensating E. M. F. derived from 54 on the commuted winding 34. This compensating E. M. F. is preferably of same phase as that of the supply and can, as is 50 known, be derived from the supply in a number of ways. The brushes are shown as being displaced by about $180/n$ degrees with respect to the axis of the main flux due to 7. This is the preferred position in this case 55 but the brushes need not stand just in that position.

In Fig. 2 the two windings 7, 8 responsible for the main flux through each part of the rotor and stator laminations have been 60 replaced by a single winding 97 embracing all the stator laminations. This substitution can always be made whether the windings 7 and 8 are connected in series or in parallel. One auxiliary stator winding 99 is so disposed as to produce a magnetization coaxial

with the main flux and another auxiliary stator winding 67 is so disposed as to produce a magnetization displaced by about $180/n$ degrees with respect to the main flux. The rotor carries a short-circuited winding 70 embracing all the rotor laminations and responsive to a flux due to 97. For the sake of clearness this winding has been shown as consisting of two interconnected windings, 24, 25, the interconnections being the same as those in Fig. 1. The rotor also carries a commuted winding 34 embracing only part of the rotor laminations and placed so as to be within the inductive influence of 99 and without that of 67. The switch 71 is shown 75 in the starting position. Winding 97 is out of circuit whereas 67, 99 and the commuted winding 34 by way of the brushes 36, 37 are all connected in series across the mains 1, 2 with the interposition of the regulatable transformer 3. The brushes 36, 37 are displaced by such an angle from the axis of 99 that those ampere turns of the commuted winding which are coaxial with 99 practically equal and oppose the ampere turns in 99. The ampere turns of the commuted winding 80 which are coaxial with 99 do duty as armature ampere turns and produce the starting torque with the motor flux due to the rest of the ampere turns of 34. This motor flux 85 is directed along an axis displaced by $180/n$ degrees from that of 99 and would induce a current in the short-circuited winding 24, 25 thus greatly reducing the torque per ampere if its effect on that winding were not 90 neutralized by 67. The winding 67 is disposed along an axis parallel to this motor flux and dimensioned to produce a flux equal in magnitude to the motor flux. The flux 95 due to 67 threads the short-circuited winding only and threads it in a direction opposed to that of the motor flux. The magnitude of the starting torque can be varied by varying at 5 the E. M. F. impressed on 100 this starting circuit. When a sufficient speed has been reached switch 71 is thrown on to point 106 thus bringing 97 and 24, 25 into 105 play and converting the machine into a self-excited shunt induction motor. 110

In Fig. 3 the E. M. F. impressed on the starting circuit is derived from the main winding 97 which, in this case, is connected to the mains at starting. The rotor windings are identical with those described in connection with the previous figures but the 115 stator carries three auxiliary windings two of which are placed along axes parallel to the axis of the main winding, the third being displaced by $180/n$ degrees with respect thereto. The E. M. F. impressed on 97 is 120 derived from the transformer 3 and can be regulated at 5. The E. M. F. derived from 97 and impressed on the starting circuit can be regulated at 120. The switches are shown 125 in their starting position. From 120 the 130

current passes through 99 and 34 in opposite directions, and the effect of the working current conducted through 34 is thus neutralized as far as 24, 25 is concerned. From 5 brush 36 it flows through 66, 67 and switch 71 back to the mains. Winding 66 produces the motor flux and 67 produces an equal flux which does not thread 34 but which threads 24, 25 in a direction 10 current conducted through 34 is thus neutralizing the effect of the latter on 24, 25. When the motor has reached a sufficient speed switch 71 is opened and if compensation be desired then switch 21 is closed thus 15 impressing on the commuted winding an E. M. F. of approximately the same phase as that of the supply and derived from 66 which winding did duty as motor field winding at starting. In Fig. 3 a current 20 flows in the short-circuited winding 24, 25 during starting, this current does not contribute to the initial torque but increases the total current taken by the motor at starting. A component of the main flux to which 25 this current is due does however contribute to the increase of the useful motor field. A motor connected as shown in Fig. 3 will not race and will be automatically converted into a self-excited shunt induction motor 30 as the speed increases. It is advisable not to impress the full line voltage on 97 until the motor has reached a sufficient speed.

In order to provide for an easy accommodation of the various motor windings, the 35 stator and rotor laminations can be divided into two longitudinally displaced groups of laminations such as 44, 45 and 46, 47 of Fig. 4. This figure shows the mechanical disposition of the windings which are diagrammatically indicated in Fig. 3. It has already been pointed out that the winding 40 permanently closed on itself was indicated in the previous figures as consisting of two interconnected windings mainly for the sake of simplicity and ease of illustration. This winding is shown in a practical form 45 in Fig. 4 where it consists of an ordinary squirrel-cage wound through both groups of rotor laminations. This squirrel-cage has 50 been designated by the two numerals 24, 25 so as to draw attention to the fact that it is the equivalent of the two interconnected windings 24, 25 shown in the other figures.

In Fig. 5 the rotor is identical with that 55 described for instance in connection with Fig. 3. There are two main stator windings 7, 8 and an auxiliary stator winding 98. The switches are shown in the starting position. The two main windings are connected in 60 parallel and to the mains. They magnetize in opposite directions with reference to the short-circuited winding and induce no currents in the latter. An E. M. F. derived from one of them, here 7, at the points 51 65 and 120 is impressed on a circuit comprising

the commuted winding 34 and the auxiliary winding 98. The latter is disposed along an axis parallel to that of 36, 37 and in such a manner that the flux it produces does not link with 34 but threads the short-circuited 70 winding in a direction opposed to that of the flux set up by the working current conducted through 34. The effect of this working current on the short-circuited winding is thus neutralized. The torque is due to 75 the main flux produced by 7, and to the current conducted through 34 by way of the brushes 36, 37 which are preferably displaced by $180/n$ degrees with respect to the axis of 7. The magnitude of the torque can be regulated by varying at 120 the E. M. F. impressed on 34 and 98. When the motor has reached a sufficient speed then the current is reversed through 8 by means of 53 thus bringing the short-circuited rotor 85 winding into play. If phase compensating is desired then switch 71 is moved on to 106 and 120 adjusted, if required, to secure the desired power factor.

In Fig. 6, the commuted winding is short-circuited by means of the brushes 36, 37 along an axis displaced with respect to the axis of 7. The switches are shown in the starting position, and windings 7 and 8 are connected across the mains and magnetize 90 in opposite directions with reference to the short-circuited rotor working winding at starting. The auxiliary stator winding 125 coaxially disposed to 8 is closed on an impedance 126. The auxiliary stator winding 130 67 displaced by $180/n$ degrees with respect to 125 is connected in series with the two main windings 7 and 8. The current induced in 34 produces two sets of ampere turns, the one coaxial with 7 is neutralized 135 by the ampere turns in 7 and does duty as armature ampere turns; the other is displaced by $180/n$ degrees with respect to 7 and is responsible for the torque producing motor field. The current in 34 is the secondary to the primary in 7 and is therefore 140 of practically same phase but of opposite sign to it. The primary current is taken through 67 which produces a flux equal to the motor flux but threading the short-circuited winding in a direction opposed to 145 that of the motor flux thus neutralizing the effect of the latter on that winding. The E. M. F. at the terminals of 7 and 8 is the same but the phase and the magnitude of 150 the flux due to 7 would differ from the phase and the magnitude of the flux due to 8 if 8 were not faced by a short-circuited secondary as is 7 by the winding 34. Such differences between the two main fluxes 155 would cause a current to flow in the short-circuited rotor working winding and would reduce the torque per ampere. To avoid this I also provide a short-circuited secondary for the winding 8 by disposing the 160

auxiliary winding 125 in inductive relation to 8 and I preferably close it on an impedance 126. This impedance can be so adjusted as to practically eliminate the 5 effect of the main fluxes on 24, 25 at starting. When the motor has reached a sufficient speed the current in 8 is reversed thus bringing the short-circuited rotor winding into play, switch 71 is moved on to point 106 10 and the circuit of 125 is opened.

Having fully described my invention, what I claim as new and desire to secure by Letters Patent of the United States, is:

1. In an alternating current motor, the 5 combination with a stator, of a laminated rotor provided with a permanently short-circuited winding and a commuted winding, said short-circuited winding extending over all the rotor laminations and said commuted 10 winding extending over a part only of the rotor laminations, and means disposed on the stator for producing a main flux through each of the rotor windings.
2. In an alternating current motor, the 25 combination with a stator, of a laminated rotor containing two longitudinally displaced groups of laminations and provided with a permanently short-circuited winding and a commuted winding, said short- 30 circuited winding extending over both groups of laminations and said commuted winding extending over only one group of laminations, and means disposed on the stator for producing a main flux through 35 each group of the rotor laminations.
3. In an alternating current motor, a 40 stator containing two longitudinally displaced groups of laminations, means for producing a main flux through each group of laminations, a laminated rotor provided with a permanently short-circuited winding and a commuted winding, said short-circuited winding extending over all the rotor laminations and said commuted winding extending 45 over a part only of the rotor laminations.

4. In an alternating current motor, a 50 stator containing two longitudinally displaced groups of laminations, means for producing a main flux through each group of laminations, an auxiliary winding on the stator, a laminated rotor provided with a permanently short-circuited winding and a commuted winding, said short-circuited winding extending over all the rotor laminations and said commuted winding extending 55 over a part only of the rotor laminations.

5. In an alternating current motor, a 60 stator containing two longitudinally displaced groups of laminations, means for producing a main flux through each group of laminations, and an auxiliary winding on one group of stator laminations adapted to magnetize along an axis coinciding with that of the main flux through that group, a laminated rotor provided with a permanently short-circuited winding and a commuted winding, said short-circuited winding extending over all the rotor laminations and said commuted winding extending 65 over a part only of the rotor laminations.

short-circuited winding and a commuted winding, said short-circuited winding extending over all the rotor laminations and said commuted winding extending over a part only of the rotor laminations.

6. In an alternating current motor, a 70 stator containing two longitudinally displaced groups of laminations, means for producing a main flux through each group of laminations, two auxiliary windings on the stator, a laminated rotor provided with a permanently short-circuited winding and a commuted winding, said short-circuited winding extending over all the rotor laminations and said commuted winding extending 75 over a part only of the rotor laminations.

7. In an alternating current motor, a 80 stator containing two longitudinally displaced groups of laminations, means for producing a main flux through each group of laminations, three auxiliary windings on the stator, a laminated rotor provided with a permanently short-circuited winding and a commuted winding, said short-circuited winding extending over all the rotor laminations and said commuted winding extending 85 over a part only of the rotor laminations.

8. In an alternating current motor, a 90 stator containing two longitudinally displaced groups of laminations, means for producing a main flux through each group of laminations, an auxiliary winding on one group of laminations adapted to magnetize along an axis approximately coinciding with that of the main flux through that group and another auxiliary winding on one group of laminations adapted to magnetize along 95 an axis displaced by about $180/n$ degrees with respect to that of the main flux through that group, a laminated rotor provided with 100 a permanently short-circuited winding and a commuted winding, said short-circuited winding extending over all the rotor laminations and said commuted winding extending 105 over a part only of the rotor laminations.

9. In an alternating current motor, a 110 stator containing two longitudinally displaced groups of laminations, means for producing a main flux through each group of laminations, an auxiliary winding on each group of laminations adapted to magnetize along an axis approximately coinciding with that of the main flux through that group and another auxiliary winding on one group of laminations adapted to magnetize along 115 an axis displaced by about $180/n$ degrees with respect to that of the main flux through that group, a laminated rotor provided with a permanently short-circuited winding and a commuted winding, said short-circuited winding extending over all the rotor laminations and said commuted winding extending 120 over a part only of the rotor laminations.

10. In an alternating current motor, a 125 stator containing two longitudinally dis-

placed groups of laminations, means for producing a main flux through each group of laminations, a laminated rotor provided with a permanently short-circuited winding and a commuted winding, said short-circuited winding extending over all the rotor laminations and said commuted winding extending over a part only of the rotor laminations, and means for compensating the motor.

10 11. In an alternating current motor, a stator containing two longitudinally displaced groups of laminations, means for producing a main flux through each group of laminations, an auxiliary winding on the stator, a laminated rotor provided with a permanently short-circuited winding and a commuted winding, said short-circuited winding extending over all the rotor laminations and said commuted winding extending over a part only of the rotor laminations, and means for directing the flow of a current in said commuted winding.

12. In an alternating current motor, a stator containing two longitudinally displaced groups of laminations, means for producing a main flux through each group of laminations, two auxiliary windings on the stator, a laminated rotor provided with a permanently short-circuited winding and a commuted winding, said short-circuited winding extending over all the rotor laminations and said commuted winding extending over a part only of the rotor laminations, and brushes for conductively conveying a current into said commuted winding.

13. In an alternating current motor, a stator containing two longitudinally displaced groups of laminations, means for producing a main flux through each group of laminations, three auxiliary windings on the stator, a laminated rotor provided with a permanently short-circuited winding and a commuted winding, said short-circuited winding extending over all the rotor laminations and said commuted winding extending over a part only of the rotor laminations, and brushes for conductively conveying a current into said commuted winding.

14. In an alternating current motor, a stator containing two longitudinally displaced groups of laminations, means for producing a main flux through each group of laminations, a rotor containing two longitudinally displaced groups of laminations and provided with a permanently short-circuited winding and a commuted winding, said short-circuited winding extending over both groups of laminations and said commuted winding extending over only one group of laminations.

15. In an alternating current motor, a stator containing two longitudinally displaced groups of laminations, means for producing a main flux through each group of laminations, an auxiliary winding on the

stator, a rotor containing two longitudinally displaced groups of laminations and provided with a permanently short-circuited winding and a commuted winding, said short-circuited winding extending over both groups of laminations and said commuted winding extending over only one group of laminations, and brushes for conductively conveying a current to the commuted winding.

16. In an alternating current motor, a stator containing two longitudinally displaced groups of laminations, means for producing a main flux through each group of laminations, two auxiliary windings disposed on the stator, a rotor containing two longitudinally displaced groups of laminations and provided with a permanently short-circuited winding and a commuted winding, said short-circuited winding extending over both groups of laminations and said commuted winding extending over only one group of laminations, and brushes for conductively conveying a current to the commuted winding.

17. In an alternating current motor, a stator containing two longitudinally displaced groups of laminations, means for producing a main flux through each group of laminations, three auxiliary windings disposed on the stator, a rotor containing two longitudinally displaced groups of laminations and provided with a permanently short-circuited winding and a commuted winding, said short-circuited winding extending over both groups of laminations and said commuted winding extending over one group of laminations, and brushes for conductively conveying a current to the commuted winding.

18. In an alternating current motor, a stator containing two longitudinally displaced groups of laminations, means for producing a main flux through each group of laminations, an auxiliary winding on one group of laminations adapted to magnetize along an axis coinciding with that of the main flux through that group, a rotor containing two longitudinally displaced groups of laminations and provided with a permanently short-circuited winding and a commuted winding, said short-circuited winding extending over both groups of laminations and said commuted winding extending over one group of laminations, and brushes for conductively conveying a current to the commuted winding.

19. In an alternating current motor, a stator containing two longitudinally displaced groups of laminations, means for producing a main flux through each group of laminations, an auxiliary winding on one group of laminations adapted to magnetize along an axis coinciding with that of the main flux through that group, another aux-

- iliary winding on one group of laminations adapted to magnetize along an axis displaced by about $180/n$ degrees with respect to that of the main flux through that group,
- 5 a rotor containing two longitudinally displaced groups of laminations and provided with a permanently short-circuited winding and a commuted winding, said short-circuited winding extending over both groups of
- 10 laminations and said commuted winding extending over one group of laminations, and brushes for conductively conveying a current to the commuted winding.
20. In an alternating current motor, a
- 15 stator containing two longitudinally displaced groups of laminations, means for producing a main flux through each group of laminations, an auxiliary winding on each group of laminations adapted to magnetize
- 20 along an axis coinciding with that of the main flux through that group, another auxiliary winding on one group of laminations adapted to magnetize along an axis displaced by about $180/n$ degrees with respect
- 25 to that of the main flux through that group, a rotor containing two longitudinally displaced groups of laminations and provided with a permanently short-circuited winding and a commuted winding, said short-circuited winding extending over both groups of
- 30 laminations and said commuted winding extending over one group of laminations, and brushes for conductively conveying a current to the commuted winding.
- 35 21. In an alternating current motor, a
- stator containing two longitudinally displaced groups of laminations, a winding embracing both groups of laminations and producing a main flux through each of said
- 40 groups, an auxiliary winding on each group of laminations adapted to magnetize along an axis coinciding with that of the main flux through that group, another auxiliary winding on one group of laminations adapted to
- 45 magnetize along an axis displaced by about $180/n$ degrees with respect to that of the main flux through that group, a rotor containing two longitudinally displaced groups of laminations and provided with a permanently short-circuited winding and a commuted winding, said short-circuited winding extending over both groups of laminations and said commuted winding extending over one group of laminations, and brushes for
- 50 conductively conveying a current to the commuted winding.
22. In an alternate current motor, a stator containing two longitudinally displaced groups of laminations, a winding embracing both groups of laminations and producing a
- 60 main flux through each of said groups, an auxiliary winding on each group of laminations adapted to magnetize along an axis coinciding with that of the main flux through that group, another auxiliary winding on
- 65 one group of laminations adapted to magnetize along an axis displaced by about $180/n$ degrees with respect to that of the main flux through that group, a rotor containing two
- 70 longitudinally displaced groups of laminations and provided with a permanently short-circuited winding extending over both groups of laminations and said commuted winding extending over one group of laminations, brushes for conductively conveying
- 75 a current to the winding, means for connecting the commuted winding and all the auxiliary windings in series relations at starting and means for deriving the E. M. F. impressed on this series circuit from the stator
- 80 winding embracing both groups of laminations.
23. In an alternating current motor, a
- rotor containing two longitudinally displaced groups of laminations and provided
- 85 with a permanently short-circuited winding extending over both of said groups, and a commuted winding extending over only one of said groups, means for producing a transformer flux through each group of rotor
- 90 laminations, and means for producing a motor flux through each group of laminations at starting.
24. In an alternating current motor, a
- stator containing two longitudinally displaced groups of laminations, means for producing a main flux through each group of laminations, a laminated rotor provided
- 95 with a permanently short-circuited winding and a commuted winding, said short-circuited winding extending over all the rotor laminations and said commuted winding extending over a part only of the rotor laminations and means for directing the flow of the current in the commuted winding.
